(57) **CLAIM**

The ornamental design for a hat brim, as shown and described.

DESCRIPTION

FIG. 1 is a perspective of a first embodiment of a hat brim according to the invention;

FIG. 2 is a top plan view of the hat brim of FIG. 1;

FIG. 3 is a front elevational view of the hat brim of FIG. 1; FIG. 4 is a side elevational view of the hat brim of FIG. 1; FIG. 5 is a rear elevational perspective view of the hat brim of FIG. 1; and,

FIG. 6 is a bottom, plan view of the hat brim of FIG. 1. The broken line portions of the above drawings are for illustrative purposes only and do not form part of the design claimed herein.
